UNITED STATES PATENT OFFICE.

ABRAHAM ANDERSON, OF GALESBURG, ILLINOIS.

WINDMILL.

SPECIFICATION forming part of Letters Patent No. 242,245, dated May 31, 1881.

Application filed February 2, 1881. (Model.)

To all whom it may concern:

Be it known that I, ABRAHAM ANDERSON, a citizen of the United States, resident at Galesburg, in the county of Knox and State of Illinois, have invented certain new and useful Improvements in Windmills; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification, in which—

Figure 1 is a vertical section. Fig. 2 is a detail. Fig. 3 is a top view. Figs. 4, 5, and 6 are details.

This invention relates to windmills; and it consists in the construction hereinafter described.

In the drawings hereto annexed, A represents the tower carrying the structure. Secured to this by bolts passing through lugs b is the supporting-plate B, upon which is located the table C.

D is the bottom plate of the table, consisting of an annulus having inner flange, d, with bolt-seats d' and tread d'', having the channel d'''.

E is an annulus having flange e, with exterior screw-threaded lugs, e', said flange forming a rabbet to receive the periphery of plate D.

Formed upon the inside of annulus E are the tapered studs or journal-arms e'', these studs and lugs e' being at the ends of right-angled diameters.

Journaled upon studs e'' are the wheels E', whose tread is in channel d'''.

F is another annulus having flanges f f', one with bolt-seats f'', the other with turned-up lugs f''' and stud f'', carrying a roller, F', on its under side. On its under side, between the flanges f f', annulus F has the channel f'', concentric with channel d''' of plate D. On its upper side this annulus F has the tread f'''.

G is another annulus rabbeted like annulus E, and having tapered studs g, carrying wheels G'. Projecting from this annulus is the arm H, having the two seats or open sockets h h', with bolt-holes g' g'', and having the eye h''' turned to the side from the open sockets.

I is the cover-plate, being an annulus having inner flange, y, with bolt-seats y' and outer

flange, y'', and the channel y''' between the flanges. Formed on this annulus is a lug, y'', screw-threaded, and on the same side, but within, a threaded hole, y''' is made. To the other side of this annulus is placed the lower plate, J, of a bearing.

These plates and annuli, as described, are put together and are held by bolts K passing through the seats on the inside and fastened by nuts. The table is then secured to plate B by bolts k passing through lugs e' on plate E and lugs k' on plate B. This forms a turn-table capable of moving with slight pressure.

The plate J contains the bearing-blocks j j, and has the screw-threaded lugs j' j' and end openings, j'' j''.

J' is the cover-plate, constructed similar to plate J.

L is the spider for carrying the fan-arms, consisting of the seats l, hub l', and journal l'', passing through hub l', having the bearing-portions l', and carrying the eccentric M, with pin m at its inner end. Secured to this pin m by box n is the pitman N, for connecting with the machinery below.

Placed in seats l are the ends p of the arms P, being held therein by plate Q, having seats q, in which the arms partly rest, and nut Q' on pin q', held in hub l'.

Fastened to arms P are the sail-bearing bars R.

r are plates having seats r', in which rest the arms P and outside seats, r'', in which rest the bars R.

p' are outside plates, having seats p'' for the outer edges of bars R to rest in, the two plates r and p' being held together and to arms P by bolts p'', which pass inside of bars R.

Cut in bars R are the oblique kerfs r''' for the reception of the sails R'.

Secured to top or cover plate, I, at lug y'' and hole y''' is a bridge, S, channeled underneath at s, and carrying at each end a pulley, s''. At the outer end of S is the eye s'', in which is the bolt s''' for the attachment of joint T, to which is held by bolt t and arms t t' the lever U, whose upper end, u, is journaled to a post, V, by which it is swiveled in eye h'' of arm H, the other end, u', carrying adjustable weights W.

Running from end u' is a cord, X, which passes over pulleys s'' down into the tower.

In seats h h' the tail is bolted.

The weight W regulates the speed by keeping the sails up to the desired point with regard to the wind, and by operating cord X the sails can be thrown out of the wind. The overhanging lips of the various parts of the table and the closed construction of the bearing for the journal l' keep out the weather. Roller F' takes the strain when there is great pressure on the sails.

10 What I claim is—

1. Plate D, having channel d^3 , annulus E, provided with tapered studs e^3 , wheels E', annulus F', provided with channel f^5 and tread f^6 , annulus G, having tapered studs g , and wheels

G', in combination with plate I, having channel y^3 , as set forth.

2. Arms P, bars R, and fastening-plates r and p' , all combined substantially as described.

3. Hub l' and seats l, in combination with arms P, plate Q, having seats q, and nut Q', substantially as described.

In testimony whereof I affix my signature in presence of two witnesses.

ABRAHAM ANDERSON.
